ATTORNEY.

UNITED STATES PATENT OFFICE.

FLORA BENSON, OF ANGLETON, TEXAS.

DESIGN FOR A PAPER DOLL.

209.

Specification for Design.

Patented Jan. 17, 1922.

Application filed June 30, 1920. Serial No. 393,190. Term of patent 14 years.

To all whom it may concern:

Be it known that I, FLORA BENSON, a citizen of the United States, residing at Angleton, in the county of Brazoria and State of Texas, have invented a new, original, and ornamental Design for a Paper Doll, of which the following is a specification, reference being had to the accompanying drawing, forming part thereof, which is a front view of a rabbit standing on its hind legs.

I claim:

The ornamental design for a paper-doll, as shown.

FLORA BENSON.
